BLOWER

Robert A. Mayne, Dayton, Ohio

Application November 13, 1944, Serial No. 563,234

6 Claims. (Cl. 230—134)

1

This invention relates to a blower and more particularly to a blower of the centrifugal type.

An object of this invention is to provide a blower having the fan blades arranged to interlock an annular ring in such a manner that the fan may be easily assembled by unskilled labor and at the same time produce a rigid, dependable and efficient fan assembly at a low cost of production.

Another object of this invention is to provide fan blades having tabs clamped between a pair of rings or hoops in such a manner that the blades are held in a rigid relationship with respect to each other and at the same time the parts are easily assembled.

Another object of this invention is to provide aerodynamic fan blades for use in a fan of the centrifugal type.

Another object of this invention is to provide extensions projecting from the ends of the blades, the width of each extension being equal to the spacing of the blades, so that the blades are held in spaced relation by the extensions being positioned edge to edge on the retaining means.

Other objects and advantages reside in the construction of parts, the combination thereof and the mode of operation, as will become more apparent from the following description.

In the drawings:

Figure 1 is a perspective view of a centrifugal type blower.

Figure 2 is an enlarged fragmentary detail view taken substantially on the line 2—2 of Figure 1.

Figure 3 is a fragmentary view showing a step in the assembly.

Figure 4 discloses a fan blade before assembly.

Figure 5 is a cross sectional view taken substantially on the line 5—5 of Figure 4.

Figure 6 is a cross sectional view of a modified fan blade.

Figure 7 is a fragmentary enlarged perspective view showing the hook arrangement of the tab as it appears on the stamping of the blade before assembly.

Figure 8 shows a spider-like support for the fan assembly.

Figure 9 is a cross sectional view taken substantially on the section line 9—9 of Figure 8.

In the manufacture of fan blades various methods of supporting the blades have been used. For example, in some fan assemblies, the blades are integral with the marginal rims, as shown in my copending application for United States Letters Patent Serial No. 525,810 filed March 8, 1944, for Centrifugal fan. In other fan assem-

2

bles the blades have been riveted to the rims, welded to the rims or seated in sockets or notches formed in the rims.

In the device disclosed herein, each of the blades is provided with extesions that are held in position by clamping rings, the width of the extensions being such that the extensions are used in spacing the blades from each other by abutting each other edge to edge.

10 Referring to the drawings, the reference character 10 indicates a fan blade having a curved body portion 12. In order to produce an aerodynamic fan blade, the marginal portion 14 has been formed into a substantially tear-shaped contour.

Each blade is provided with an extension portion 16 that is initially formed into a hook-shape by bending the end 18, as clearly shown in Figure 7. The width of the extension or tab portion 16 is equal to the spacing between the blades. The blades are assembled upon a pair of bars 20, each having a rectangular cross sectional area, as clearly shown in Figure 2. The hook extensions 16 are merely hooked over the edges of the bars 20, the extensions 16 adjoining each other along the edges. The bars 20 have a length equal to the circumference of the blower, as measured on the inside of the tabs. After all of the blades used in the blower have been 30 assembled on the bars 20, the bars 20, together with the blades, may be passed through suitable rollers which bend the ends 18 into contact with the inner margins of the bars 20 and at the same time curve the bars 20, so as to form the 35 assembly into a circular or cylindrical contour. The ends of the bars 20 may be buttwelded, so as to form hoops or rings for supporting the fan blades.

A clamping or shroud ring 22, that has a cross 40 sectional area simulating an angle bar, is forced upon the outer periphery of the extensions 16, so as to rigidly clamp the extensions between the flanged portion 24 of the ring 22 and the ring 20. The ring 20 has an inwardly directed flange 45 portion 26 which functions as a reenforcing ring to maintain the blower assembly in true circular form. The ring 22 may be formed in any one of a plurality of methods. It may be formed by spinning the metal, it may be formed by stamping, which is the preferred mode of forming the ring, or it may be formed from an angle bar that has been curved into circular formation. The ring 22 may be spot-welded or riveted at spaced intervals to some of the extensions 55 16 and the ring 20.

Each end of the blower may be supported upon a pair of hubs 32 by diametrically disposed spokes 30. Instead of two spokes for each hub, three, four or any suitable number may be used. In the preferred embodiment disclosed herein, each spoke consists of a pair of round bars 34, having the ends spot-welded to the inwardly directed flange 26 and the center portion 36 formed into a semi-circular shape, so as to embrace the hub 32. The spokes may be welded together at 38, so as to rigidly hold the spokes around the hub. Instead of utilizing a pair of bars forming the diametrically disposed spokes, the spokes could be formed in any other suitable manner, as for example by stamping the spokes out of sheet metal.

Referring to the modification disclosed in Figures 8 and 9, a spider has been shown for supporting the fan assembly. This spider includes a hub 40 provided with an axially disposed aperture 42 and a plurality of radially disposed pairs of apertures 44. This hub is mounted upon a suitable drive shaft 46, as is well known to those skilled in the art. The fan assembly is supported in spaced relation from the hub by a plurality of U-shaped members 50, having the ends of the legs seated in the apertures 44 and fixedly secured thereto either by press-fitting or by welding.

The bight or transverse bar 52 of each U-shaped member 50 is positioned in contact with selected blades 10 and welded thereto. A portion of the legs is curved at 54 so as to snugly fit the contour of the blades. By utilizing two spaced bars forming the legs of the U-shaped member joined by the transverse bar, a supporting spider is provided that has greater rigidity than if the spoke-like members were to end when coming into contact with the blades. Furthermore, the transverse bar and the curved portion of the U-shaped member are positioned on the convex side of the blades and, so to speak, push the blades when driving the fan. This mounting assembly is easily produced, is efficient, has the required strength and at the same time low impedance to the flow of air.

In assembling the parts the squirrel-cage-like fan may be first assembled, then the hub 40 and the U-shaped members 50 assembled. The squirrel-cage-like fan assembly and the hub may then be placed in a cradle or a jig, holding the hub in concentric relation with respect to the fan blades, the cradle or jig holding the fan in a true circular relation, the bight of the U-shaped supports being welded to selected blades while the assembly is held in the jig, so as to produce a fan assembly wherein the fan and the hub are concentrically disposed with respect to each other.

For some purposes the shroud ring 22 may be omitted. In order to improve the appearance of the fan assembly and to secure the blades in position, the extensions together with the rings, or in other words, the ends of the fan assembly, may be galvanized. In the event the shroud ring is eliminated and it is desired to produce a high speed fan, the extensions may be located on the inside of the rings 20, so that the centrifugal force exerted upon the blades is transmitted through the extensions outwardly to the rings 20. In such an event, the tabs would be folded outwardly over the rings 20, then galvanized, so as to partly conceal the tabs and so as to bond the extensions to the rings 20.

Although the preferred embodiment of the de-

vice has been described, it will be understood that within the purview of this invention various changes may be made in the form, details, proportion and arrangement of parts, the combination thereof and mode of operation, which generally stated consist in a device capable of carrying out the objects set forth, as disclosed and defined in the appended claims.

Having thus described my invention, I claim:

1. In a blower assembly the combination including a pair of spaced rings and sheet metal arcuate blower blades mounted between the rings, each of the sheet metal blower blades terminating in a pair of extensions, the extensions of each blade lying in a common plane substantially normal to a portion of the arcuate blower blade, the width of the extensions being equal to the spacing of the blades so that the edges of the extensions of adjacent blades contact each other, the ends of the extensions being folded inwardly and under the rings so as to hold the blades in position with respect to the rings.

2. In a blower assembly a pair of spaced rings, sheet metal blower blades mounted between the rings, each of the sheet metal blower blades terminating in a pair of extensions, the extensions of each blade lying in a common plane substantially normal to a portion of the arcuate blower blade, the width of the extensions being equal to the spacing of the blades so that the extensions of adjacent blades contact each other and overlie the rings, the ends of the extensions being folded inwardly and under the rings so as to hold the blades in position with respect to the rings, and a pair of juxtaposed rings overlying the extensions so as to clamp the extensions between the first rings and the second rings, said second rings counteracting the centrifugal force exerted by the blades when the blower is in motion.

3. In a blower assembly a pair of spaced rings, sheet metal blower blades mounted between the rings, each of the sheet metal blower blades terminating in a pair of extensions, the extensions of each blade lying in a common plane substantially normal to a portion of the arcuate blower blade, the width of the extensions being equal to the spacing of the blades so that the extensions of adjacent blades contact each other and overlie the rings, the ends of the extensions being folded inwardly and under the rings so as to hold the blades in position with respect to the rings, and a pair of juxtaposed rings overlying the extensions so as to clamp the extensions between the first rings and the second rings, said second rings counteracting the centrifugal force exerted by the blades when the blower is in motion, said second rings having inwardly directed flange portions for reenforcing the margins of the blower to hold the ends of the blower circular.

4. In a blower assembly the combination including a pair of spaced rings and sheet metal arcuate blower blades mounted between the rings, each of the sheet metal blower blades terminating in a pair of extensions, the extensions of each blade lying in a common plane substantially normal to a portion of the arcuate blower blade, the width of the extensions being equal to the spacing of the blades so that the edges of the extensions of adjacent blades contact each other, said extensions being placed edge to edge in contact with said rings, and a second pair of rings cooperating with the first pair of rings to clamp the extensions in position.

5. In a blower assembly the combination including a pair of spaced rings and sheet metal ar-

cuate blower blades mounted between the rings, each of the sheet metal blower blades terminating in a pair of extensions, the extensions of each blade lying in a common plane substantially normal to a portion of the arcuate blower blade, the width of the extensions being equal to the spacing of the blades so that the edges of the extensions of adjacent blades contact each other, said extensions being placed edge to edge in contact with said rings, and a second pair of rings cooperating with the first pair of rings to clamp the extensions in position, the ends of said extensions overlapping at least one of said rings to hold the rings axially.

6. In a blower assembly the combination including a pair of spaced rings and sheet metal arcuate blower blades mounted between the rings, each of the sheet metal blower blades terminating in a pair of extensions, the extensions of each blade lying in a common plane substantially normal to a portion of the arcuate blower blade, the

width of the extensions being equal to the spacing of the blades so that the edges of the extensions of adjacent blades contact each other, the extensions contacting the rings, the ends of the extensions being folded over the edge of the rings to hold the blades and the rings in fixed axial relation with respect to each other.
